(74) Attorney, Agent, or Firm — Murray, Ziel & Johnston; Aaron Powell

(57) **CLAIM**

The ornamental design for a soap dispenser, as shown and described.

DESCRIPTION

FIG. 1 is a top, front, left side perspective view of a soap dispenser, showing my new design;

FIG. 2 is a bottom, front, left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The evenly broken lines illustrate portions of the soap dispenser and form no part of the claimed design.

1 Claim, 8 Drawing Sheets
